UNITED STATES PATENT OFFICE.

GEORGE L. HUNTRRESS, JR., OF WINCHESTER, MASSACHUSETTS.

WATER-GAGE.

1,181,139.

Specification of Letters Patent.

Patented May 2, 1916.

Application filed April 7, 1910. Serial No. 553,928.

To all whom it may concern:

Be it known that I, GEORGE L. HUNTRRESS, Jr., a citizen of the United States, and a resident of Winchester, in the county of Middlesex, State of Massachusetts, have invented an Improvement in Water-Gages, of which the following description, in connection with the accompanying drawings, is a specification, like letters on the drawings 10 representing like parts.

This invention relates to water gages and the like and, among other objects, aims to provide improved means for securing the gage glass in position without danger of 15 breaking said glass.

The character of the invention may be best understood by reference to the following description of an illustrative embodiment thereof shown in the accompanying 20 drawings, wherein:

Figure 1 is a front elevation of a water gage embodying my invention; Fig. 2 is a side view of Fig. 1, partly in section and partly in elevation; Fig. 3 is a rear view of 25 Fig. 1; Fig. 4 is a section taken on line 4—4 of Fig. 2; Fig. 5 is a rear elevation of a modification; Fig. 6 is a side elevation of Fig. 5, partly in section; and Fig. 7 is a section taken on line 7—7 of Fig. 6.

In high pressure water gages it is necessary to employ a glass for disclosing the water level which will be sufficiently strong to withstand the pressure and at the same time should clearly indicate the height of 35 the water in the gage. Herein a reflex glass is used, known as the "Klinger" type. This glass has the form of a comparatively thick block provided on its inner surface with grooved faucets at such angles as to eliminate all light from the vacant space back of the glass and at the same time permit the 40 passage of light through that portion of the grooves covered with water or other liquid.

Heretofore, considerable difficulty has 45 been found in securing the glass in the gage without cracking. One of the objects of my invention is to provide a water gage in which the glass will be held in place with a uniform pressure without danger of 50 cracking.

The illustrative water gage shown herein as embodying my invention comprises a water container or tube 1 (Fig. 1) adapted

to be connected to pipes 2 leading from the upper and lower parts of a boiler or other 55 water receiver. A face of the tube 1 is provided with upper and lower lateral apertures 3 (Fig. 2). Each of these apertures may be closed by a Klinger reflex or other glass 7, a suitable gasket strip 9 being provided for such glass.

I will now describe provision for securely seating these glasses on the apertured face of said tube with a uniform pressure. The devices for retaining the upper and lower 65 glass may be the same and hence a description of one will suffice for both. Such a device comprises a frame or housing 11 having a portion shaped to receive the glass block 7 and having an aperture 13 for exposing the glass and permitting the level of the water in the tube 1 to be seen. The outer face of the glass may rest against a gasket 17 in the frame 11 to prevent injury to said glass. The frame 11 has open ends to permit the introduction of the tube 1 therein.

To draw the glass block 7 firmly over the lateral apertures 3 in the tube 1 with an even pressure sufficient to prevent leakage therebetween and effectually withstand the 80 high pressure within the tube, there is provided wedge means, herein in the form of opposed wedges 19 having flat faces resting against the flat back of the tube 1 and having inclined faces coöperating with 85 similarly inclined faces of the back 20 of the frame 11. These wedges 19 may be thrust toward one another to press the glass block 7 tightly over the aperture 3 by an adjusting screw 23 having its ends oppositely threaded into apertures in ears 25 on said wedges 19, said ears projecting out from said frame through recesses 26 therein. To prevent longitudinal movement of said screw on said frame, said screw is provided 90 with a central flange 27 accurately fitting in an arc-like recess 29 in the external face of said frame 11. An end of said screw may be squared to facilitate its adjustment.

The rotation of the screw 23 will draw 100 the wedges 19 equally toward one another and will press against the back of the tube 1 with an even pressure and as a result the glass 7 in turn will be drawn onto the apertured face of said tube with an even pressure. Since the pressure on the glass is

uniform there will be no danger of setting up strains therein which might result in its cracking or mutilation.

In assembling the parts first the glass block is placed in the frame 11 on the gasket 17. Then an end of the tube 1 is introduced within the frame with its aperture properly positioned over said glass. The adjusting screw 23 is then turned to draw said parts firmly together as described. In a similar manner the upper glass may be positioned and secured over the upper aperture in the tube 1.

It will be observed that by this construction the unequal pressure liable to occur where a number of different adjustments are used to press the parts together is eliminated, since the parts herein are drawn securely together by one adjustment through the turning of one instrumentality.

Referring to Figs. 5, 6 and 7, I will now describe another modification of wedge means for securing the parts together. The tube, glass and frame may be substantially the same as those previously described. The parts are retained together by a wedge clamping member 33 having a flat face 35 resting against the back of the tube 1 and oppositely inclined sides 36, said member being prevented from dropping out of place by screws 37 threaded into said member and loosely entered through said frame. To initially position the member 33 on the back of said tube there may be provided a screw 39 threaded into said frame and having a rounded end for engagement with a similarly shaped depression in said member. After said member has been initially positioned against the back of the tube it may be firmly set against the latter by sliding wedges 41 having flat sides resting against the inner surface of said frame and inclined sides for engagement with the inclined sides 36 of the member 33 referred to. These wedges 41 may be slid in toward one another by screws 43 threaded into bosses 45 on said frame and having heads 47 occupying T-shaped recesses in the outer ends of said wedges 41. Said screws may have squared ends 49 whereby they may be turned to slide the wedges 41 toward one another.

In assembling the parts, after the glass block is set in place in the frame; the end of the tube is introduced therein. The clamping member 33 is then initially positioned against the back of the tube by setting up the screw 39. The rounded end of the latter co-operates with the similarly shaped depression in said member and permits the latter to adjust itself evenly on the back of said tube. The adjusting screws 43 are then turned to force the wedges toward one another and draw the glass block securely onto its seat with a tight fit.

65 In each of the modifications it will be ob-

served that the gage comprises an upper and a lower glass. It will be observed that these glasses are spaced apart and are each provided with separate securing means for retaining them in place.

If steam and water were in the tube opposite the same glass the upper portion of the latter and of said frame would be hotter than the lower portion of the glass and frame. This difference in temperature 75 would expand the upper portion of the frame more than the lower portion. The unequal pressure thus caused on the glass would be liable to crack the latter. By my invention the glass disclosing the steam is separated 80 from the glass disclosing the normal water level. As a result the temperature on each glass is substantially uniform and the danger of cracking the glass from unequal strains thereon due to differences in temperature is eliminated and the life of the glass is prolonged. It will, therefore, be observed that the whole arrangement and construction of the device contribute to the maintenance of the glass on its seat with a uniform 90 pressure throughout. The wedge means construction in its broader aspect is claimed in Letters Patent No. 1,059,733, granted to me on April 22, 1913.

Having described illustrative embodiments of my invention, without limiting myself thereto what I claim as new and desire to secure by Letters Patent is:

1. A gage comprising, in combination, a fluid container; transparent means; and 100 means to secure said transparent means to said container including wedges and means for moving said wedges toward one another to vary their wedging action.

2. A gage comprising, in combination, a 105 fluid container having an aperture therein; transparent means for covering said aperture; a frame for said parts; wedges co-operating with said frame and container; and means to operate said wedges toward one 110 another to secure said transparent means to said container.

3. A gage comprising, in combination, a fluid container having an aperture therein; transparent means for covering said aperture; a frame for said parts; wedges co-operating with said frame and container; and a screw for drawing said wedges toward one another to secure said transparent means to said container.

4. A gage comprising, in combination, a fluid container; a glass for disclosing the level of a liquid in said container; a frame receiving said glass and container; wedges interposed between the latter and said frame 125 and tapering toward one another; and means to cause said wedges to approach one another to secure said glass to said container.

5. A water gage comprising, in combination, a water tube having a lateral aperture 130

therein; a glass therefor; a frame carrying the latter; wedges coöperating with said frame and tube; a screw for setting up said wedges to seat said glass to cover said aperture and means coöperating with said frame for preventing longitudinal movement of said screw.

In testimony whereof, I have signed my name to this specification, in the presence of two subscribing witnesses.
